UNITED STATES PATENT OFFICE

142,505

DESIGN FOR AN ELECTRIC WATER HEATER FOR STOCK TANKS AND THE LIKE

Boyd W. Warner, North Manchester, Ind., assignor to The Warner Brooder & Appliance Corporation, North Manchester, Ind., a corporation of Indiana

Application May 25, 1945, Serial No. 119,729

Term of patent 14 years

(Cl. D81—10)

To all whom it may concern:

Be it known that I, Boyd W. Warner, a citizen of the United States and resident of North Manchester, in the county of Wabash and State of Indiana, have invented a new, original, and ornamental Design for an Electric Water Heater for Stock Tanks and the like, of which the following is a specification, reference being had to the accompanying drawing, forming a part thereof.

In the drawing,

Fig. 1 is a perspective view taken from one side

of an electric water heater for stock tanks and the like embodying my new design, and Fig. 2 is a perspective view taken from the opposite side thereof.

The dominant features of the design reside in the portions shown in full lines.

I claim:

The ornamental design for an electric water heater for stock tanks and the like, substantially as shown and described.

BOYD W. WARNER.
